SADIROD SOLE PLATE AND METHOD OF
MAKING

Horace C. Wright, Chicago, Ill., assignor to Chicago Flexible Shaft Company, Chicago, Ill., a corporation of Illinois

Application September 3, 1936, Serial No. 99,223

7 Claims. (Cl. 76—101)

This invention relates to sadirons and has special reference to a sole plate for sadirons and of a method for making the same.

The invention contemplates a sole plate of the type having a flat lower face, sides which converge to a pointed front, and a transverse back edge, the side walls being beveled inwardly from bottom to top and the top of the sole plate having a large cavity covering a substantial portion of the top surface of the sole plate and defined by marginal side walls, the top also having a longitudinally disposed thermostat well defined by side walls separating the well from the main cavity. The main cavity is adapted to receive a heating element and a retaining element as disclosed in the copending application of Ivar Jepson, Serial No. 38,533, filed August 30, 1935. In the past, the sole plates of this character have been made from steel or malleable iron through forging operations, which method has been satisfactory in some respects but highly unsatisfactory in others. The cost of producing the sole plates in quantity has been high because of the close tolerances allowed in the size of the cavity which has resulted in a considerable proportion of rejects. Even when the tolerances are maintained within the closest limits with which the forging operation can be reasonably successful the variation in the size of the cavity is such as to introduce major difficulties in the manufacture and assembly of the iron. Another source of serious trouble is in the fact that the forging operations must be conducted hot and, under the circumstances, there is a tendency toward the formation of scale and pits resulting from scale, on the bottom surface of the cavity. Since the heat from the heating element must be carried across this face these irregularities have a material effect on the rate of heat transfer. More than this, however, the presence of pits or points along the surface where the heating element cannot be pressed firmly against the surface results in a burning out of the heating element because in these small areas the heat is not properly conducted away from the resistance wire of the heating element, causing the wire to become overheated and to fuse, thus opening the circuit through the element. The production of a sole plate of this character which would be free of the defects enumerated on a commercially feasible basis has, therefore, been an important problem.

Among the objects of the invention is the provision of a generally improved sole plate of greater uniformity in production, of lower cost, of im-

proved properties, and wherein the bottom of the cavity therein is smooth and bright, the dimensions of the cavity are consistently uniform and the side walls of the cavity are vertical with respect to the bottom thereof and the provision of a method for making the sole plate whereby certain economies are effected and wherein the base plate and side walls are independently formed and thereafter brazed together to form the sole plate.

Other objects and advantages will become apparent from the following description and the accompanying drawing, in which—

Figure 1 is an expanded view showing the parts entering into the construction of the sole plate; 15

Fig. 2 is a perspective view of the finished sole plate;

Fig. 3 is a section on the line 3—3 of Fig. 2, and

Fig. 4 is a section on the line 4—4 of Fig. 2. 20

The structure of the sole plate will be apparent from a description of the method for making the same when considered in connection with the drawing and attention is, therefore, first directed to Figure 1. A base plate designated 25 generally by the numeral 5 is first cut from a sheet of rolled metal having plane upper and lower faces. Advantageously this will be a sheet of cold rolled steel or other cold rolled metal, as in this manner the scale and pitting associated 30 with hot working processes are avoided and the sheet will, without further processing, have a smooth and bright upper and lower surface. In the present instance, the base plate 5 is cut from a sheet of about $\frac{1}{8}$ " stock, this being the thickness 35 desired in the cavity portion of the sole plate. The base plate 5 is then subjected to a swaging operation along the upper edge of its periphery so as to bevel at least a portion of the edge thereof as shown at 6 through which operation a considerable amount of grinding is eliminated in the finishing operations. The marginal side walls designated generally by the numerals 7 40 and 8 are cut to length from a straight rod of stock which is rolled to the desired cross-sectional dimensions, a sloping side as shown at 9 being rolled on the stock at the mill. These rods are preferably made of cold rolled steel in the usual manner. The side members 7 and 8 are then subjected to a forming operation through 45 which they are given a curvature conforming to the curvature of the side of the base plate 5 so that when placed thereon the outer beveled sides 9 will form a continuation of the beveled portion 6 of the base plate and the forward ends 11 and 50

55

12 thereof will abut each other at the forward end of the base plate. A back wall member 13 is likewise cut to length from rod stock which is cold rolled to the proper cross-sectional shape and 5 dimensions at the mill. This member may have a beveled side 14 of the same or a different slope from the beveled side 9 and is adapted to be interposed at the rear of the base plate 5 between the spaced ends of the side members 7 and 8 so that 10 the side 14 forms a continuation of the rear edge of the base plate 5. The member 13 is, in this instance, drilled and tapped, as shown at 15, for the purpose of supporting other parts of the iron structure. Rods 16 and 17 also preferably of 15 cold rolled steel, though not necessarily so, are cut to size to form the side walls for the thermostat well, as shown in Fig. 2. A block 18 which may be tapped and drilled, as shown at 19, is cut to size to be interposed between the well walls 16 20 and 17 against the base plate 5 for the purpose, in this instance, of supporting a portion of the thermostat mechanism. A boss 21 which is drilled and tapped, as shown at 22, is cut of somewhat greater height, in this instance, than 25 the side walls 7 and 8 and is adapted to be positioned with its end against the base plate 5 in the manner shown in Fig. 2, thereby serving as an end wall for the thermostat well and for the purpose of attaching the super-structure of the iron. A second boss 23 having an annular shoulder 24 adjacent its upper end is cut in a suitable 30 manner and is of such height that the distance between the lower end thereof and the lower face of the shoulder 24 is substantially equal to 35 the height of the side walls 7 and 8, whereby when positioned in the manner shown in Fig. 2 the shoulder 24 overhangs and confines the upper edge of the side walls 7 and 8.

The elements are assembled together in the 40 positions shown in Fig. 2 and are firmly held in these positions by any suitable means as, for example, by spot-welding or by the use of a suitable jig. While I have satisfactorily employed spot-welding for the purpose I prefer to employ 45 a jig, the particular structure of which forms no part of this invention and is consequently not shown.

With the elements held or secured in the positions described, the parts are brazed together in 50 a brazing furnace according to methods well known in the art. The brazing operation involves the use of a brazing medium which may consist of wire, chips, or paste, of a suitable brazing metal as is well known in the art. In this 55 instance, I prefer to use wire as the brazing medium which may be either copper wire or a wire made of a copper zinc alloy. This brazing medium is placed along the junction of the surfaces to be brazed and the assembled sole plate is passed through a brazing furnace. The brazing 60 oven is of the well known type employing control of the atmosphere in the furnace which are commonly known as controlled atmosphere furnaces, suitable types being manufactured by 65 the General Electric Company and The Electric Furnace Company. In this furnace the temperature of the sole plate assembly is brought to a point at which the brazing medium becomes molten whereupon the molten metal flows 70 through capillarity into the interface between the parts, the atmosphere in the furnace being controlled as to its chemical action both upon the sole plate and the brazing medium. As the sole plate assembly moves on through the brazing 75 furnace the temperature is gradually reduced so

that the brazing medium solidifies and the temperature of the composite structure is reduced to a point at which it may be removed from the furnace without detrimental effect.

The brazed sole plate is then removed from the 5 jig, the annular beveled edges 25 are ground to smoothness and to the proper slope, the edges and the bottom of the plate are polished and subsequently electro-plated according to the usual procedure in finishing sole plates of this character. 10

The finished and plated sole plate as shown in Fig. 2, when assembled in the iron cannot be distinguished from a sole plate made by the use of the foregoing operation. The sole plate is, however, characterized by the smooth and bright bottom of the cavity 26, by the freedom of this bottom from pits or scale, by the accurate inside dimensions of the pit 26, and by the smooth vertical sides of the pit which meet the bottom at a sharp right angle. These properties are of material value in the sole plate in that the absence of pits or scale greatly reduces the number of irons which become defective in use due to the burning out of the heating element. The smoothness 20 and brightness of the surface substantially facilitates the transfer of heat to the sole plate. The accuracy in the dimensions of the cavity permits the heating element and the retaining element subsequently inserted in the cavity to fit 30 therein within close limits and materially reduces the cost in that heating elements of a single fixed size may be utilized in the assembly of the irons as distinguished from the provision of a plurality of sizes differing from each other a small amount, as has been heretofore necessary to obtain a close fit. 35

Wholly aside from the improved properties of the sole plate the method permits of substantial reduction in the cost of manufacturing the sole 40 plate since the various elements may be turned out by large scale production methods and the various steps of the method may be conducted on a large scale production basis with a relatively small percentage of rejected product. This 45 is contrasted with the forging operations of the prior art in which the forging of this piece constitutes a very difficult forging operation because of the necessity of maintaining close limits in size and the necessity for obtaining in the production at least a reasonably smooth and scaleless surface at the bottom of the cavity. Material savings are also made in the finishing operations by the reduction in the amount of grinding required to prepare the article for plating operations. 55

I am aware that numerous alterations and changes may be made in the invention as herein described without departing from the spirit of the invention and I do not wish to be limited except as required by the prior art and the scope of the appended claims, in which— 60

I claim:

1. The combination in a sole plate for sadirons, of a base plate comprising a flat rolled metal sheet having smooth surfaces free from pits and scale, upstanding marginal preformed walls thereon of a cross-section to prevent warpage of the base plate and defining a top cavity for the reception of a heating element between said walls, and means within the cavity for attaching the super-structure of an iron, the sole plate being characterized by the accurate dimensions of said cavity, smoothness of the bottom of said cavity, and by the fact that said elements are se- 75

- cured in position by a capillary layer of brazing material.
2. The method for making sadiron sole plates of the type having a heating element cavity and annular walls which includes the steps of cutting a base plate from smooth, bright stock of rolled cross-section, cutting peripheral side walls of required length from straight smooth stock, bending said walls to the required curvature, securing 10 said parts in the desired relationship and thereafter brazing said parts together in a furnace.
3. A method for making sadiron sole plates comprising cutting a base plate from a flat sheet of smooth rolled metal, preshaping peripheral 15 side walls for said plate, assembling said side walls on said plate to provide a top cavity therein having a smooth bottom, and thereafter brazing said parts together in a brazing furnace to produce successive plates wherein the size and 20 shape of the cavities are maintained within close limits.
4. A method for making sadiron sole plates comprising cutting a base plate from a flat sheet of rolled metal having a smooth scaleless surface, preshaping peripheral side walls and centrally disposed walls for said plate from rolled metal, assembling said walls on said plate, applying a brazing medium to the junction between said parts, and thereafter passing said assembly through a brazing furnace while retaining the parts in said position to produce successive plates in which the spaces between the walls are maintained uniform within relatively close limits.
5. A method for making sadiron sole plates comprising cutting a base plate from a flat sheet of cold rolled steel, preshaping peripheral walls for said plate from rods of predetermined rolled cross-sectional shape, preshaping walls for a centrally disposed thermostat wall, forming attaching means for the super-structure of the iron, assembling said parts in the desired relation, brazing said parts together in a brazing furnace while maintaining the parts in accurately fixed relation to produce uniformity of size in successive plates, and thereafter grinding, polishing and plating the bottom and sides of the sole plate thus produced.
6. The method for making sadiron sole plates comprising cutting a base plate from a flat sheet of cold rolled steel, beveling the edges of said base plate to slope inwardly from bottom to top, preshaping peripheral walls for said plate from rods having a beveled side rolled thereon, of a slope substantially identical with the slope of the beveled edges on said base plate so that when placed together said bevels are substantially coplanar, assembling the side walls on said plate, and thereafter brazing said parts together in a 20 brazing furnace.
7. The combination in a sole plate for sadirons, of a base plate comprising a flat rolled metal sheet having smooth surfaces free from pits and scale, upstanding marginal walls of rolled section 25 thereon defining a top cavity for the reception therein of a heating element, the base plate and walls being of a thickness to substantially resist warpage of the sole plate in service, centrally disposed base walls on said plate within the cavity defining a thermostat well, and means within the cavity for attaching the super-structure of an iron, the sole plate being characterized by the accurate dimensions of said cavity, smoothness 30 of the bottom of said cavity, and by the fact that 35 said elements are secured in position by a capillary layer of brazing metal.

- cured in position by a capillary layer of brazing material.
2. The method for making sadiron sole plates of the type having a heating element cavity and annular walls which includes the steps of cutting a base plate from smooth, bright stock of rolled cross-section, cutting peripheral side walls of required length from straight smooth stock, bending said walls to the required curvature, securing 10 said parts in the desired relationship and thereafter brazing said parts together in a furnace.
3. A method for making sadiron sole plates comprising cutting a base plate from a flat sheet of smooth rolled metal, preshaping peripheral 15 side walls for said plate, assembling said side walls on said plate to provide a top cavity therein having a smooth bottom, and thereafter brazing said parts together in a brazing furnace to produce successive plates wherein the size and 20 shape of the cavities are maintained within close limits.
4. A method for making sadiron sole plates comprising cutting a base plate from a flat sheet of rolled metal having a smooth scaleless surface, preshaping peripheral side walls and centrally disposed walls for said plate from rolled metal, assembling said walls on said plate, applying a brazing medium to the junction between said parts, and thereafter passing said assembly through a brazing furnace while retaining the parts in said position to produce successive plates in which the spaces between the walls are maintained uniform within relatively close limits.
5. A method for making sadiron sole plates comprising cutting a base plate from a flat sheet of cold rolled steel, preshaping peripheral walls for said plate from rods of predetermined rolled cross-sectional shape, preshaping walls for a centrally disposed thermostat wall, forming attaching means for the super-structure of the iron, assembling said parts in the desired relation, brazing said parts together in a brazing furnace while maintaining the parts in accurately fixed relation to produce uniformity of size in successive plates, and thereafter grinding, polishing and plating the bottom and sides of the sole plate thus produced.
6. The method for making sadiron sole plates comprising cutting a base plate from a flat sheet of cold rolled steel, beveling the edges of said base plate to slope inwardly from bottom to top, preshaping peripheral walls for said plate from rods having a beveled side rolled thereon, of a slope substantially identical with the slope of the beveled edges on said base plate so that when placed together said bevels are substantially coplanar, assembling the side walls on said plate, and thereafter brazing said parts together in a 20 brazing furnace.
7. The combination in a sole plate for sadirons, of a base plate comprising a flat rolled metal sheet having smooth surfaces free from pits and scale, upstanding marginal walls of rolled section 25 thereon defining a top cavity for the reception therein of a heating element, the base plate and walls being of a thickness to substantially resist warpage of the sole plate in service, centrally disposed base walls on said plate within the cavity defining a thermostat well, and means within the cavity for attaching the super-structure of an iron, the sole plate being characterized by the accurate dimensions of said cavity, smoothness 30 of the bottom of said cavity, and by the fact that 35 said elements are secured in position by a capillary layer of brazing metal.
